CAN PUNCTURING DEVICE

Carl Swyers, St. Albans, W. Va.

Application March 25, 1946, Serial No. 656,921

2 Claims. (Cl. 30—10)

1

The present invention relates to so-called devices and tools which are adapted to hold and puncture venting and pouring holes in commodity cans; for example, evaporated milk cans, this is a manner to facilitate dispensing of the contents from the can.

As the opening and general statement of the invention implies, the art to which the present invention relates is highly and actively developed and there are many and varied types of can puncturing devices known and patented. Usually, these devices are characterized by pointed penetrating prongs which are pressed forcibly down against the top of the can, whereby to penetrate same and to provide diametrically opposite holes, the latter being used selectively for venting and pouring purposes. The present invention, like existing structures in the same category, possesses many elements which are basically similar to those found in said prior devices. However, in carrying out the specific principles of the instant invention, I have evolved and produced a simpler and more practical structure which is possessed of a number of distinguishable and appreciable improvements.

In carrying out my aims, I provide a can holding shelf, the same being a part of a special fixture and said fixture including means at the upper end of a back plate thereof to accommodate a swingably mounted frame, said frame being provided with finger actuating means and can top puncturing prongs.

More specifically, novelty is predicated upon an upstanding back plate forming a part of the wall fixture, the upper end of said plate having portions bent to provide spaced bearings and also a portion, between said bearings bent to provide a resilient detent, the latter being releasably engageable with the can to assist in conveniently holding same in a puncturable position on said shelf.

Other objects, features and advantages will become more readily apparent from the following description and the accompanying illustrative drawings.

In the drawings, wherein like numerals are employed to designate like parts throughout the views:

Figure 1 is a front view of the complete assemblage forming the can holding and puncturing device.

Figure 2 is a side or edge elevation of the same, this showing, in dotted lines, the can and the operation of the puncturing tool forming a part of the complete device.

2

Figure 3 is a top view which may be said to be taken approximately on the plane of the line 3—3 of Figure 1, this looking in the direction of the arrows.

Figure 4 is a bottom view occurring on the line 4—4 of Figure 2 looking upwardly in the direction of the arrows.

In using the expression "device" I have in mind the complete assemblage, that is, the overall structural means which is characterized by the so-called wall fixture or bracket A on the one hand, and complementary puncturing tool B on the other. The can, which is conventional, is indicated at C whereas the wall or other supporting surface is denoted at D.

The bracket or fixture A comprises, as before indicated, a horizontal shelf 6, this of general rectangular form as shown in Figure 3. Attached to and rising from the inner end of the shelf is a vertical plate or wall 7 which is adapted to bear against and is designed to be secured to the support D. The longitudinal edges of the shelf are provided with upstanding lips 8 forming retaining flanges for the lower or bottom portion 20 of said can C. The numeral 9 designates a diagonal brace which is connected by a bend 10 to the front or outer end of the shelf. This brace is of general V-shaped form as shown in Figure 2 and the terminal end portion is provided with a laterally bent ear 11 which is secured by a fastening 12 to the support B. The length of the brace or leg 9 is such as to place the attaching ear 11 in vertical alignment with the upstanding wall 7. This wall 7 as shown in Figure 1 is of rectangular flat form and the upper end thereof is provided with struck-out tongues. There are three of such tongues. The outermost tongues 13 are shaped and bent to provide the attaching ears to accommodate the fastening screws 14. The bent portions of said tongues are fashioned into bearings 15. The remaining tongue is located between the ears 13 and is bent as at 16 and again bent as at 17 and flared up and outwardly as at 18 to provide a spring detent. This detent is engageable with the upper puncturable end of the can C as is brought out to advantage by the dotted line showing in Figure 2.

The tool, or can puncturing means B comprises a wire or similar frame 19 whose bent end portions 20 form journals and these are mounted for rotation in the bearings 15. The central or bight portion of the frame is fashioned into a finger ring 21 and the adjacent portions 22 are brought together to form a shank which accommodates a sleeve or collar 23 in the manner

shown. The opposed side members of the frame proper carry a cross rod 24 which is in turn provided with laterally bent ends 25 (see Figure 2) and said ends terminate in pointed puncturing prongs 26. The prongs are adapted to press down and force through the top of the can C, for purposes of forming the holes (not shown) as usual.

In practice, the can is placed on the shelf 6 and the shelf is braced by the leg or brace 9 and the firmly attached vertical wall 7. The lower portion of the can is held against side slipping and sliding by the confining and retaining flanges 8. The hinged frame or tool B is raised to the dotted line position shown in Figure 2 and the prongs 26 are brought down against the top of the can. By exerting a downward pull on the finger ring 21 it is possible to force the prongs through the can top in an obvious manner. It might be added, as before indicated, that the can is held at the upper portion, this against slipping by the aforementioned resilient detent formed by the features 17 and 18.

While in the foregoing there has been shown and described the preferred embodiment of this invention it is to be understood that minor changes in the details of construction, combination and arrangement of parts may be resorted to without departing from the spirit and scope of the invention as claimed.

I claim:

1. A can holding and puncturing device of the class described comprising a can holder including a horizontally disposed shelf having an upstanding wall, said wall terminating at its upper end in bearings and said bearings serving to accommodate a can puncturing tool, said bearings being spaced apart and said wall also having a laterally and downwardly bent springy detent, said detent being situated between said bearings and adapted to snap over and engage the upper end of the can, said shelf being provided with side lips forming can confining flanges to facilitate holding said can in place during the punc-

turing step, said shelf also including a depending diagonal bracing leg terminating in an attaching ear for securing to a fixed supporting surface, and a wire frame hingedly mounted in said bearings and provided with can puncturing elements.

2. A milk can basing, holding and top puncturing device of the type shown and described comprising a sheet material wall fixture, said fixture being of a single piece of material and embodying a horizontally disposed shelf provided at one end with an upstanding wall, said wall terminating at its upper end in spaced bearings and being provided, between said bearings with a lateral and downwardly bent detent, said detent overlying said shelf and being at right angles to said wall and having an upturned free end portion, the end of the shelf opposite to the end carrying said wall being provided with a down bent diagonally disposed bracing leg terminating in an attaching ear, said ear being in an approximate plane with said upstanding wall, opposed longitudinal edge portions of said shelf having upstanding lips providing can confining flanges, said flanges serving to embrace diametrically opposite portions of the base part of the milk can and said detent being adapted to rest resiliently upon the top of the can, and a wire frame having journals hingedly mounted in said bearings and provided with can puncturing elements and further including a finger ring.
